UNITED STATES PATENT OFFICE.

THOMAS LEE, OF CINCINNATI, OHIO, ASSIGNOR OF ONE-HALF TO OLIVER KINSEY, OF SAME PLACE.

FREIGHT-CAR.

SPECIFICATION forming part of Letters Patent No. 247,076, dated September 13, 1881.

Application filed July 5, 1881. (No model.)

To all whom it may concern:

Be it known that I, THOMAS LEE, of Cincinnati, in the county of Hamilton and State of Ohio, have invented a new and useful Improvement in Grain and Freight Cars, which improvement is fully set forth in the following specification and accompanying drawings, in which—

Figure 1 is a longitudinal vertical sectional view of a car equipped with my improvement. Fig. 2 is a plan view, looking from the top, with the car-roof removed. Fig. 3 is a top view of the floor, showing the arrangement of the door-guards. Fig. 4 is a perspective elevation of one of the door-guards. Fig. 5 is an end view of the car, showing arrangement of the weight, pulleys, and ropes; and Fig. 6 is a side view of the same.

The object of my invention is to construct an improved grain-car; and it consists, first, in having a chute or hopper formed centrally in the floor of the car; and, second, in providing the interior of the car with two grain-receptacles, of even size in width with the interior of the car, hinged to the edges of the chute on both sides, and adapted to be elevated so that the grain will be tilted into the central chute and be conveyed thence to suitable bins or vehicles.

Referring to the accompanying drawings, A represents the body of a car, and B an inclined chute or hopper projecting downwardly centrally from the car-floor. This chute is provided below with an ordinary cut-off plate or slide, C, for checking the flow of the grain. There is, however, no special merit claimed in this invention for the chute; hence it is not here described in detail.

Near each end of the car is a vertical partition, A', extending up near to the top or roof of the car. The interior of the car is provided with a grain-receptacle, D. This is formed of a base-plate or floor, a, composed of wood or metal, preferably the latter, and extends from the edge of the central chute to a point near the partition A'. This base-plate a is hinged along the line of the chute, at D', to the floor, and it is further provided with sides b and end c, as shown. When constructed in this manner it is obvious that this grain-receptacle

can be elevated or turned on the hinge D'. For the purpose of more readily elevating these tilting grain-receptacles, and also to furnish counter-weights for more easily raising them, pulleys E are secured at the ends of the cars, 55 near the roof within, and ropes E', secured to the base of the grain-receptacles D, pass over these pulleys and down into the chamber formed by the partitions A', when they are attached to weights F. A rope, L, is attached 60 to the under side of these weights, which extends down to a transverse shaft, M, near the floor of the car. The shaft M passes through one side of the car, and is provided with a crank, N, for elevating the tilting grain-receptacles D.

G represents a supplementary car-door used in connection with the tilting grain-receptacles. Fig. 4 shows their construction in detail. I form these doors preferably of two plates—an 70 outer one, G, and an inner one, G'. These are made of equal dimensions and provided with a vertical batten, H, between them centrally, and riveted together. The outer and inner plates have sufficient space between them to 75 permit the side pieces, b, of the tilting grain-receptacle to pass in, as shown in Fig. 3. To provide against leakage of grain between the outer and inner plates, G G', and between the outer plate, G, and the inner side of the door-post, I line the inner surface of the inner plate, G', and the outer surface of the outer plate, G, with felt, rubber, or other suitable lining or padding, K. These supplementary doors extend past the jambs of the car-doors a suitable distance, and are held in position by means of braces I, riveted to the door at I', and provided at the ends with downwardly-projecting points or lugs J, which are adapted to be placed in staples or sockets in the jambs of the car-opening or door-frame.

It will be observed in Fig. 3 that the supplementary car-doors have been removed from the doorways and placed on the car-floor longitudinally side by side. The object of this is 95 to convert the grain-car into an ordinary freight-car for common freight purposes. The supplementary car-doors G thus cover the hopper B; and suitable braces, if desired, can be placed transversely under the doors to keep them from 100

springing when freight is taken in or off the car. The grain-receptacles D form a permanent interior casing for the car, and do not diminish the floor-area or in any manner interfere with shipping goods of any character that are usually transported in box-cars.

The operation of my invention is as follows: The cut-off plate or slide C at the base of the hopper being closed and locked and the grain-receptacles secured in position, (shown in Fig. 1,) the supplementary doors G are placed in position in the doorways, so that the side plates, b, enter between the plates G G'. The car is then filled with grain, and when ready to unload the cut-off plate or slide C is drawn out, permitting the grain to pass down into proper chutes or receptacles. The cranks N are now put into operation, drawing down the weights and elevating the tilting receptacles, as shown by dotted lines x in Fig. 1.

I am aware that it is not new to use the supplementary car-doors to form a bottom for the car, and I do not claim this broadly. Heretofore it has been customary to hinge this side or supplementary door to the car; but in the present invention it is made loose and detachable, as shown.

Having thus described my invention, what I claim as new, and desire to secure by Letters Patent, is—

1. A car provided with the oppositely-dis-

posed hinged grain-receptacles D, in combination with the weights F, to be used as a counter-balance, substantially as set forth.

2. A supplementary car-door composed of two plates, G G', secured to each other, with a batten, H, between, and provided on the edges, as shown, with felt, rubber, or other packing material, substantially as and for the purpose specified.

3. The tilting grain-receptacles hinged to the floor of the car, in combination with the loose and detachable supplementary car-doors, as herein shown.

4. A grain-car having centrally through the floor the chute C, in combination with the loose and detachable supplementary doors G, as described, laid longitudinally over the chute, substantially as and for the purpose specified.

5. In a grain-car, the combination of the tilting grain-receptacles D, hinged to the car-floor, having the rope E' and weight F, the rope L, shaft M, and crank N, with the supplementary doors G, having the fastenings I, as and for the purpose specified.

In testimony that I claim the foregoing I have hereunto set my hand this 1st day of July, A. D. 1881.

THOMAS LEE.
